(57) **CLAIM**

The ornamental design for a tent, as shown and described.

DESCRIPTION

FIG. 1 is an upper perspective view of a design for a tent; FIG. 2 is a lower perspective view of the design of FIG. 1; FIG. 3 is a first side view of the design of FIG. 1; FIG. 4 is a second side view of the design of FIG. 1; FIG. 5 is a third side view of the design of FIG. 1; FIG. 6 is a fourth side view of the design of FIG. 1; and, FIG. 7 is a top view of the design of FIG. 1. The broken lines shown in the drawings depict portions of the tent and form no part of the claimed design.
